HATCHBACK CAMPER

Joseph Louis Cammarato, 11632 Bedford Court,
Germantown, Md. 20767

Filed May 29, 1973, Ser. No. 364,551

Term of patent 14 years

Int. Cl. D12—16

U.S. Cl. D12—156

FIG. 1

FIG. 2

FIG. 3

FIG. 4

FIG. 1 is a side elevational view of a hatchback camper showing my new design, the opposite side being substantially a mirror image thereof;

FIG. 2 is a top plan view thereof;

FIG. 3 is a front elevational view thereof; and

FIG. 4 is a rear elevational view thereof.

The hatchback automobile shown in broken lines in the drawing is included for illustrative purposes only.

I claim:

The ornamental design for a hatchback camper, as shown and described.
